UNITED STATES PATENT OFFICE.

WILLIAM RODERICK BARCLAY, OF LEICESTER, ENGLAND, ASSIGNOR TO UNITED SHOE MACHINERY COMPANY, OF PATERSON, NEW JERSEY, A CORPORATION OF NEW JERSEY.

MACHINE FOR COMPRESSING HEELS.

1,125,254.

Specification of Letters Patent. Patented Jan. 19, 1915.

Application filed January 13, 1910. Serial No. 537,911.

To all whom it may concern:

Be it known that I, WILLIAM R. BARCLAY, a citizen of the United States, residing at Leicester, Leicestershire, England, have invented certain Improvements in Machines for Compressing Heels, of which the following description, in connection with the accompanying drawings, is a specification, like reference characters on the drawings indicating like parts in the several figures.

This invention relates to machines for compressing sole leather blanks for boots or shoes. The machine constituting the specific embodiment of the invention herein-after described and illustrated is adapted for compressing a blank having the marginal portion of its face located out of the plane of the interior portion of the face. An example of this kind of a blank is a heel having a marginal recess in its tread face formed to receive a metal heel tip of horseshoe shape.

The invention is shown applied to a machine of the type in which the bottom of the mold cavity is formed by a device vertically movable to remove the heel from said cavity.

An important feature of the invention consists in a movable device of this nature constructed to accommodate a blank having the marginal portion of its face out of the plane of the interior portion thereof. According to the preferred construction the device is so formed and arranged that when in compressing position at the bottom of the mold cavity its marginal portion is at a different level from its central portion and when raised in said cavity all portions of its upper surface are at substantially the same level. The device shown comprises a plurality of sections which are arranged for automatic relative movement during the vertical movement of said device.

A further feature of the invention consists in arranging the marginal sections which fill the marginal recess in the heel for movement relatively to the central section in a horizontal plane. With this arrangement the marginal sections may be somewhat removed from the central section when the heel to be compressed is placed upon the device, thus permitting the central raised portion upon the tread surface of the heel to readily descend into position

between the marginal sections. The marginal sections are so arranged that in the closing movement of the dies which subject the heel to lateral pressure said dies move said sections together, bringing said sections into position to fill the recess in the heel and also subjecting the filler or bottom lift of the heel to lateral pressure. The construction may be conveniently such that the marginal sections are forced away from the central section by a spring after the dies release the heel.

Other features of the invention will be hereinafter described and referred to in the appended claims.

In the drawings,—Figure 1 is a view in plan with parts in horizontal section of a portion of a heel compressing machine according to the present invention; Fig. 2 is a vertical sectional view of the machine illustrated in Fig. 1; Fig. 3 is a view similar to Fig. 2 showing the position of the parts while the pressure is applied to the heel.

The compressing machine to which the present invention is shown applied is of the type of that illustrated in United States Letters Patent No. 776,875 dated December 6, 1904, to Tripp, to which reference may be had for a complete disclosure of parts of the machine not directly related to the present invention.

Referring to the drawings, the reference numeral 1 indicates the vertically movable head of the compressing machine and 2 the stationary follower which has engagement with the heel-seat surface of the heel. Side dies 4 are mounted upon the head for horizontal movement thereon, as is fully explained in said patent, and a breast die 6 is forced toward and from the heel in the movement of the side dies 4.

The head 1 is provided with a vertical bore beneath the mold cavity, receiving a plunger 8 which is automatically raised and lowered relatively to the head. The plunger 8 carries upon its upper end a central flat section 10 of the contour shown in Fig. 1. In the position of the parts shown in Fig. 3 the central section 10 rests upon the head 1 and supports the central portion of the heel which constitutes the filler for the horseshoe-shaped tip to be afterward applied to the heel. Two marginal sections

12, 14, are arranged between the central section 10 and the side dies 4. The marginal sections 12, 14 are connected at the rear end of the mold cavity by a pin 16 headed at each end and received in alined bores formed in said marginal sections. The pin 16, as will be obvious, limits movement of the marginal sections away from the central section. A spring 18 is arranged about the pin 16 in recesses formed in the adjacent faces of the marginal sections to move said marginal sections apart. The central section 10 is also provided with spring-pressed plugs 20 engaging the marginal sections at different points in their length for the purpose of moving said sections away from the central section.

The marginal sections 12, 14 are provided at intervals in their length with recesses 22 extending from the bottom of the sections to a point short of the upper surface of the section a distance slightly greater than the thickness of the filler piece on the heel to be compressed. The recesses 22 are entered by 25 laterally projecting pins 24 upon the central section 10.

Referring to Fig. 3, while the mold is closed upon the heel the marginal sections 12, 14 rest upon the head 1 and their upper 30 ends fill the recess in the heel in which is subsequently placed the horseshoe-shaped heel tip. When the plunger 8 is raised after the heel is released by the dies, the marginal sections are moved away from the central 35 section 10 by the springs referred to, and thereupon descend relatively to the central section until they rest upon the upper faces of the pins 24. The pins 24 are of such a height that when the marginal sections rest 40 thereon the upper surface of said sections is substantially level with the top of the central section 10, as is indicated in Fig. 2. It will be seen that in the position of the parts shown in Fig. 2 the heel rests upon a 45 surface which offers no obstruction to horizontal sliding movement of the heel out of the machine. The removal of the heel from the position shown in Fig. 1 may be accomplished by ejecting mechanism such as is 50 shown and described in the Letters Patent referred to.

It will be seen that while the plunger 8 is in its raised position the marginal sections 12, 14 are slightly removed from the 55 central section so that when the central section 10 descends below the level of the marginal portions the bottom lift of the heel may readily descend into position between the marginal sections. In the closing movement of the marginal sections effected by 60 the side dies, this bottom lift or follower is compressed laterally so that a marginal recess in the heel of a predetermined size is insured.

65 Having described my invention, what I

claim as new and desire to secure by Letters Patent of the United States is:—

1. In a machine for compressing heels, a device arranged to form the bottom of a mold cavity and constructed to be raised in the cavity to remove a compressed heel therefrom, said device comprising a plurality of sections arranged to lie at different levels in the compressing position of the device and to lie at substantially the same level in the raised position of the device.

2. In a machine of the class described, a compressing member for engaging and exerting pressure upon the face of a blank, said member comprising a central compressing portion 10, and a surrounding portion 12, 14, said portions being relatively movable and lying wholly at distinctly different elevations when in pressure exerting position.

3. In a machine for compressing heels, a device arranged to form the bottom of a mold cavity and movable within the cavity, said device comprising a plurality of interconnected heel engaging sections constructed for relative movement in a horizontal plane.

4. In a machine of the class described, the combination of a die section arranged for engagement with a portion of the lateral surface of a heel, and a separate, relatively movable die section arranged for engagement with a portion of said surface at a different point in the height of the heel.

5. In a machine for compressing heels, a device arranged to form the bottom of a mold cavity and constructed to be raised in the cavity to remove a compressed heel therefrom, said device comprising a plurality of sections constructed for relative movement in the line of movement of said device and also arranged for relative movement transverse to said line of movement of the device.

6. In a machine for compressing heels, the combination with movable dies for engaging the edge of a heel, of a device forming the bottom of the mold cavity comprising a central section and a plurality of marginal sections raised above the level of the central section and arranged for movement toward and from said central section in a horizontal plane and constructed to be forced toward the central section in the closing movement of said dies, and to be moved away from the central section in the opening movement of the dies.

7. In a machine for compressing heels, the combination with a supporting member, of a device constructed to form the bottom of a mold cavity comprising a central section arranged for vertical movement upon said supporting member and formed to engage the central portion of the heel and a marginal section for engaging the marginal portion of the heel constructed and ar-

ranged to be supported by the supporting member in the compressing position of the device and to be supported by and move with the central section in the movement of said device into ejecting position.

8. In a machine for compressing heels, the combination of an expansible mold comprising movable side dies and means for moving the same, a device forming the bottom of the mold cavity, said device comprising a plurality of heel engaging sections separate from said dies and relatively movable horizontally, and means for effecting such relative movement.

9. In a machine of the class described, the combination of a rigid die section arranged for engagement with a portion of the lateral surface of a heel, and a separate, relatively movable die section arranged for engage-

ment with a portion of said surface offset from the first mentioned portion and located at a different point in the height of the heel.

10. In a machine of the class described, a member for engaging and exerting pressure upon the face of a blank, said member comprising a central portion and a surrounding portion, said portions being relatively movable and lying in substantially parallel planes at different elevations when in pressure exerting position.

In testimony whereof I have signed my name to this specification in the presence of two subscribing witnesses.

WILLIAM RODERICK BARCLAY.
